WINDING MACHINE

Gustaf S. Beckman, Cranston, R. I., assignor to
Universal Winding Company, Boston, Mass., a
corporation of Massachusetts

Application July 7, 1932, Serial No. 621,282

19 Claims. (Cl. 242—43.3)

This invention relates to improvements in winding and like machines and consists in automatically-operated means for winding a length of reserve yarn on the end of the cop-tube or other package support before the winding of the package itself is started.

One object of the present invention is to provide a device of the character specified having yarn-controlling means for winding a reserve length of yarn on the cop-tube or package support for use in splicing to the end of another supply package in a series whereby the yarn may be caused to deliver continuously in a magazine type of creel.

Another object of the invention is to provide a device of the type specified which is capable of winding the reserve length and transferring the yarn to the thread-guide for winding the package without imposing undue strain or excessive tension on the yarn.

Another object of the invention is to provide a device of the type specified which is convenient to thread in preparing the machine for operation and which may be quickly and easily reset after each complete winding operation.

Another object of the invention is to provide a device of the type specified which is simple in construction and adapted for use with practically all types of winding machines without alteration in the arrangement of the mechanism thereof.

Further objects of the improvement are set forth in the following specification which describes a preferred embodiment of the invention, by way of example, as illustrated by the accompanying drawings. In the drawings:

Fig. 1 is a side view of a winding machine showing the essential elements thereof and illustrating the present device as applied to use therewith;

Fig. 2 is an enlarged end view of the winding machine showing the traverse-mechanism partly in section;

Fig. 3 is an enlarged view in elevation of the yarn-controlling means and the thread-guide showing their relative positions upon completion 45 of the reserve winding;

Fig. 4 is a corresponding view showing the relative positions of the yarn-controlling means and the thread-guide upon liberation of the yarn and immediately prior to its pick-up by the thread-guide;

Fig. 5 is an end view of the improved reserve winding device showing the yarn-controlling means thereof in position to guide the yarn;

Fig. 6 is a plan view of the improved device 55 shown with the cover removed and illustrating the

yarn-controlling means positioned as shown in Fig. 5;

Fig. 7 is a view corresponding to Fig. 6 showing the yarn-controlling means positioned to free the yarn; and

Fig. 8 is a sectional view on line 8—8 of Fig. 7.

Referring to the drawings, Fig. 1 illustrates a conventional type of winding machine comprising certain essential elements which are well known in the art. The operating parts of the machine are mounted on a box-like frame 2 carrying bearings for a horizontal winding-spindle 3 and a parallel cam-shaft 4 arranged therebelow. The winding-spindle 3 overhangs the forward side of the frame 2 and carries a suitable form of cop-holder 5, herein illustrated in the shape of a truncated cone, for receiving the paper cop-tube C or other yarn-receiver, for example, a wooden cone, on which the conical package is wound. The winding-spindle 3 is driven from suitable power-operated means such as a belt-pulley 6 connected to the spindle by a clutch 7. The cam-shaft 4 is driven from the spindle 3 by a train of gearing 8 enclosed in a case or housing 9 at one side of the frame 2. A pulley 11 on the end of the spindle 3 is connected by a belt 12 to drive a similar pulley 13 which, through the gearing 8, drives the cam-shaft 4 at a reduced rate of speed.

Mounted fast on the lower shaft 4 is a helically-grooved cam 14 which actuates the traverse-mechanism, next described, to reciprocate a thread-guide 16 to deposit the yarn, thread or other strand material on the package.

The traverse-mechanism is mounted on a traverse-frame 17 constituted by a horizontal bar or member 18 supported by opposite arms 19 and 21 which are pivoted to rock on the bearings 22 and 23 for the cam-shaft 4. The traverse-frame 17 is provided with an overhanging portion 24 projecting outwardly beyond the arm 19 and forming an extension of its main horizontal member 18. The two horizontal members 18 and 24 are provided with a groove 26, see Fig. 2, adapted to serve as a track or guideway for a sliding traverse-rod 27. The inner end of the traverse-rod 27 is connected to a slide 28 which carries a roller or bowl 29 engaged with the helical groove of the cam 14. The outer end of the traverse-rod 27 carries an arm 31 in which is mounted the thread-guide 16 in a manner as next described. The arm 31 is formed at its upper end with a circular opening for receiving the guide 16 which is of the "button" type having a

110

slot or groove 33 for the thread, yarn or other strand to draw through.

The outer arm 19 of the traverse-frame 17 is extended below its bearing hub, preferably in a separate arm 34 attached thereto and terminating in a counterweight 36 which tends to maintain the traverse-frame in substantially erect position. Attached to the overhanging part 24 of the traverse-frame 17 is a plate or back 37 against which the thread-guide arm 31 bears to direct the guide 16 in a course parallel to the surface on which the winding is performed. In the machine herein illustrated the traverse-frame back 37 has its bearing face 38 inclined at an angle to the axis of the winding-spindle 3 in conformity with the taper of the cone-holder 5, while in other instances the back may extend parallel to the axis of the winding-spindle when a cylindrical package is to be wound on the machine. Secured upon the traverse-frame back 37 by opposite screws 39 is a curved wire thread-bail 40 which extends parallel with the surface of the cop-tube and along which the strand slides during its traverse. In accordance with the present invention the thread-bail 40 serves to position the strand as it leads to the cop-tube C so that it will extend across the path of the thread-guide 16, whereby the latter is caused to pick up the strand upon completion of the reserve winding to thereafter traverse the yarn to wind the package.

In the present drawings the machine is illustrated as operating on a yarn strand *y* drawing off from a supply arranged below, but not herein shown. The yarn draws upwardly through a tension-device 43 of any suitable construction, thence through a sub-catcher 44 and leads across a breakage lever 45 to the thread-bail 40. In winding the package the strand *y* draws through the groove 33 in the thread-guide 16 and the reciprocation of the guide causes the yarn to be traversed longitudinally of the axis of the winding-spindle for the full length of the package to deposit it in helical coils which build up in layers to form the package.

The present improved reserve winding device is arranged in relation to the above described mechanism as next explained. The reserve winding device is attachable to and supported upon the swinging traverse-frame 17 by means of a twisted sheet-metal strip 46 constituting a bracket or standard therefor. The end of the standard 46 is slotted at 47 to receive one of the screws 48 which secure the back 37 to the traverse-frame 17. The standard 46 is also formed with an upper slot 49 which receives the shank of one of the screws 39 for the thread-bail 40. The slots 47 and 49 provide for adjusting the standard 46 on the screws 48 and 39 so that the reserve winding device may be positioned to properly locate the first coils of yarn with respect to the end of the package to be wound on the cop-tube C. After the device has been properly adjusted in position the screws 48 and 39 are tightened to rigidly attach the standard 46 to the traverse-frame 17 to position the yarn-controlling device in close proximity to the surface of the cop-tube C at its base end thereof.

The present reserve winding device embodies an auxiliary guide or yarn-controller 52 which, as herein shown, is forked to provide a curved finger 53 and a shorter straight finger 54 between which is a V-shaped crotch or guideway 56. The guideway 56 is adapted to receive the strand *y* which is maintained therein in the position illus-

trated in Figs. 1 and 3 at the commencement of the winding operation to provide for winding the reserve length of yarn on the butt end of the cop-tube C. The yarn passes across the thread-bail 40 and directly through the guideway 56 of the controller 52 to the cop-tube C. After the reserve winding is completed the controller 52 is automatically shifted into the position illustrated by full lines in Fig. 4 and shown by dotted lines in Fig. 5. Through this operation the yarn, without leaving the thread-bail 40, is transferred from the guideway 56 of the controller 52 to the groove 33 of the thread-guide 16 to be traversed during the ensuing winding operation to build the package with a warp wind.

The controller 52 is constituted as a part of a rockable lever or member 55 comprising bearing ears 57 and 59 connected by a lateral strip or crossbar 58. Projecting from the opposite end of the crossbar 58 is a finger-piece or lever 61 which serves as a means for manually rocking the member 55. The ears 57 and 59 are provided with alining holes, in which is held a rod 62 having its projecting ends journaled in bearing ears 63 bent at right-angles to the twisted upper portion of the bracket or standard 46. The crossbar 58 of the member 55 is formed with an angular latch or detent-lug 64 adapted to pass through a slot 66 in a horizontal plate or platform 67 forming a part of the standard 46 and to be engaged beneath the edge of a ratchet-disk 68 rotatable on the platform. The disk 68 is provided with a radial slot or opening 70 through which the detent-latch passes to release the member 55. Opposite the lug 64 an integral stop-finger 69 projects from the side of the crossbar 58 of the member 55. A spring 71 coiled around the horizontal pivot-rod 62 and made fast at its opposite ends to the stop-finger 69 and the standard 46 tends to rock the member 55 upon the completion of the reserve winding and the release of its detent-latch 64 from under the disk 68, whereby to alter the position of the yarn-controller 52 in the manner and for the purpose as later explained. The rocking movement of the member 55 under the action of the spring 71 is limited by the contact of its stop-finger 69 with the end of a set-screw 72 adjustable in the standard 46 to vary the extent of throw of the yarn-controller 52.

The ratchet-disk 68 is journaled on a fixed stud 73 projecting upwardly from the platform 67 on the standard 46, the top of the disk being counter-bored to accommodate a retaining flange 74 on the stud. The disk 68 is controlled by a helical wind-up spring 76 coiled about the stud 73. One end of the spring 76 is engaged in a hole 77 in the disk 68 and the other end held in a transverse slot 78 in the upper end of the stud 73, the tension of the spring tending to rotate the disk 68 in a clockwise direction as viewed in Figs. 6 and 7.

Secured fast to the upper reduced portion 79 of the disk 68 is an annular ratchet 81 having a series of peripheral teeth 82 extending throughout the greater portion of its circumference and terminating in a radial projection or stop-finger 83. The ratchet 81 is held fast on the disk 68 by means of opposite screws 84 threaded into the disk with washers 86 under their heads. The ratchet 81 projects slightly above the top of the disk 68 to adapt the washers 86 to bind thereagainst to clamp it fixedly to the disk. By loosening the screws 84 the ratchet 81 may be turned on the disk 68 to adjust the angular relation be-

tween the stop-finger 83 and the slot 70 whereby to regulate the timing of action of the yarn-controller 52. The rockable member 55 is released to permit the shifting of the controller 52 when 5 the disk 68 has been rotated to a prescribed extent to bring its slot 70 into register with the detent-latch 64.

Pivoted on a vertical stud 87 fast in the platform 67 is a lever 88 formed with a pawl 89 at 10 one end for progressively engaging the teeth 82 of the ratchet 81 to prevent retrogressive movement of the disk 68 under the action of its spring 76. A spring 90 connected at one end to an ear 91 in the lever 88, and suitably anchored 15 at the other end to the standard 46, urges the pawl 89 into engagement with the teeth 82. The lever 88 has a rearwardly-extending arm 92 adapted to be operated upon to release the pawl 89 from the ratchet in the manner and for the 20 purpose as later explained.

The ratchet-disk 68 is progressively rotated in a counterclockwise direction, as viewed in Figs. 6 and 7, by means of a lever 93 carrying a pawl 94 engageable with the teeth 82 of the ratchet 81. 25 The pawl 94 is of spring-metal riveted to the side of the lever 93 at 95 and having a finger 96 at its upper end bent at right-angles to extend through a slot 97 in the end of the lever. Projecting from one side of the pawl 94 is another 30 finger 98 bent forwardly to adapt its end to be engaged by the curved finger 53 of the yarn-controller 52. The lever 93 is pivoted on a depending portion 99 of the platform 67 by means of a stud 100 with the side of its lower arm engaged 35 by the end of a leaf-spring 101. The spring 101 has a bent portion 102 overlying the forward side of the standard 46 and riveted thereto at 103, see Fig. 2. The lever 93 is rocked to turn 40 the ratchet-disk 68 by the intermittent engagement of the thread-guide arm 31 with its lower end. As the ratchet-disk 68 is progressively rotated in the manner indicated the pawl 89 engages with the teeth 82 to prevent its retrogressive movement. Upon the return movement of 45 the lever 93 the spring-pawl 94 yields to permit its end to slide back across one tooth to engage with a succeeding tooth. A stop-finger 105 secured fast on the standard 46 by a screw 104 is positioned to lie in the path of the lever 93 to 50 limit its return movement. By adjusting the finger 105 to raise or lower its outer end the range of movement of the lever 93 may be regulated to vary the extent of rotative movement of the ratchet-disk 68 under the action of the pawl 94.

55 The lower end of the lever 93 carries a contact-element or bunter 106 adapted to be engaged by the side of the thread-guide arm 31 at the end of each rearward stroke of the latter. The bunter 106 is secured fast on the lever 93 by means of a screw 107 passing through a slot 108 therein. By loosening the screw 107 the bunter 106 may be adjusted on the lever 93 to insure its proper contact with the guide-arm 31 to effect actuation of the ratchet-disk 68.

60 The disk 68 is provided with a stop or pin 109 projecting from its periphery in position to engage against the side of the lever 93 after the disk has been turned to a position to cause 65 action of the yarn-controller 52. The lever 93 is caused to make one more stroke after turning the disk 68 to release the detent-latch 64 on the member 55, thereby turning the disk through the space of one tooth to bring the pin 109 against 70 the side of the lever to hold the latter from

moving back into position to be forcibly engaged during the further operation of the machine.

The post or stud 87 on the top of the standard 46 is formed with a threaded hole 112 for receiving a screw 113 by means of which a cover 80 or casing 114 is attached to the device to enclose its operating mechanism. The top of the casing 114 is provided with an aperture to receive the stud 73 whereby the casing is arranged to closely overlie the mechanism enclosed therein. The method of operation of the complete machine is as next explained in detail.

85 As hereinbefore noted, the reserve winding device or yarn-control unit may be attached to standard types of winding machines to cooperate with the traversing means thereof without alteration in the mechanism of the machine. The device may be mounted on the swinging traverse-frame of the machine by attaching it thereto with screws 39 and 48 already in place. The 90 bracket 46 is adjusted in position with the yarn-controller 52 located with its crotch or guideway 56 at a point opposite the base end of the cop-tube C, just outside the zone of traverse of the thread-guide 16. To prepare the machine for 95 winding the cop-tube C is placed on its mandrel or holder 5 and secured thereto by suitable means as usually provided. With the thread-controller 52 held in initial position by the engagement of its detent-latch 64 in under the edge of the 100 ratchet-disk 68 the machine is threaded up in the manner as next explained.

105 The strand y of yarn, thread or the like is drawn up from its source of supply through the tension-device 43 and slub-catcher 44, thence 110 across the breakage lever 45 and led over the thread-bail 40. The end of the strand is passed through the guideway or crotch 56 in the yarn-controller 52 and attached to the cop-tube C in any suitable manner as usually employed. 115 Before starting the machine to operate the traverse-frame 17 is swung back into erect position with the thread-guide 16 bearing against the surface of the cop-tube C in the manner as indicated in Fig. 2 of the drawings.

120 The machine is started to operate by throwing the starting lever to connect the driving pulley 6 with the clutch 7 which is fast on the winding-spindle 3. The spindle 3 is thus caused to be driven to rotate the cop-tube C to wind the strand 125 thereon as it feeds across the thread-bail 40 and through the yarn-controller 52. Concurrently with the rotation of the winding-spindle 3 the traverse-rod 27 is reciprocated by the cam 14 to cause the thread-guide 16 to traverse back 130 and forth longitudinally of the axis of the cop-tube C.

135 During the initial stages of the operation of the machine the yarn-controller 52 remains fixed in the position shown in Figs. 1 and 3 with the strand y drawing across the top of the thread-bail 40 as shown most clearly in Fig. 3 and leading through the crotch 56 in the controller to cause it to be coiled about the base end of the cop-tube C without traversing it thereon. 140 The strand y feeds from the thread-bail 40 through the yarn-controller 52 and thence directly to the surface of the cop-tube C as it draws downwardly from the controller in tangent relation to the periphery of the tube, see Fig. 2. 145 That portion of the strand drawing down from the controller to wind about the base end of the cop-tube C is beyond the range of traverse of the thread-guide 16, as will be apparent by reference to Fig. 3. Fig. 3 shows the thread- 150

guide 16 at the extreme end of its inward traverse or, more specifically, at the limit of its traverse in the right-hand direction, and the yarn drawing through the controller 52 feeds to the surface 5 of the cop-tube C at a point outside the range of the thread-guide to prevent the strand from entering the slot or groove 33 in the guide. The yarn will thus be caused to make a number of turns y^2 about the base end of the cop-tube C 10 to provide a reserve length for splicing to another cop in a series; the number of turns in, or the length of, this reserve winding being determined by the setting of the control device.

Referring to Figs. 6, 7 and 8, it has been explained that the ratchet 81 is adjustable rotatively on the disk 68 and by regulating the position of the stop-finger 83 with reference to the release slot 70 in the disk the device may be set to release the yarn-controller after any desired number of 20 strokes of the thread-guide 16. That is to say, the position of the stop-finger 83 with respect to the release slot 70 in the disk 68 determines the extent to which the disk must be moved intermittently by the action of the pawl 94 on the lever 93. It will be understood that the winding-spindle makes several revolutions during one complete 25 traverse of the thread-guide and for the purpose of the present explanation it may be considered that the cop-tube C is revolved six times to one movement of the thread-guide 16 from the inward 30 extreme of its traverse outwardly and back again. As illustrated in Fig. 7 of the present drawings the ratchet 81 is adjusted on the disk 68 in such position that it requires the disk to be turned 35 through the space of seven teeth to carry the slot 70 in the disk into position to release the detent-latch 64 on the controller-member 55. Consequently, with such an adjustment of the device 40 the cop-tube will make six times seven or forty-two revolutions before the controller is released so that forty-two coils or turns of the yarn will be wound onto the base of the cop-tube to provide the reserve length.

As the initial reserve winding operation proceeds the thread-guide arm 31 is caused to make contact with the bunter 106 on the lower end of the lever 93 at the end of each rearward stroke of the thread-guide. As the thread-guide arm 31 moves away from the bunter 106 on the forward 50 traverse the spring 101 rocks the lever 93 to slide its pawl 94 rearwardly on the ratchet 81 to engage a succeeding tooth thereof. At the next rearward traverse movement of the thread-guide its arm 31 will again rock the lever 93 to advance 55 the ratchet in the same manner, and in this way the disk 68 is intermittently rotated until its slot or opening 70 is turned to a position in register with the opening 66 in the shelf 67.

At this juncture the detent-latch 64 is released 60 to swing through the opening 70 in the disk 68 as the member 55 is rocked by its spring 71. The member 55 is rocked downwardly until its stop-finger 69 contacts with the end of the stop-screw 72 and the control-member 52 is thus shifted 65 from its initial position as illustrated in Fig. 3 to the down position as shown in Fig. 4. As the controller 52 is rocked on its pivot the strand y held therein is released from its crotch or guide-way 56 in the manner as illustrated in Fig. 4. 70 Upon its release the strand y will be drawn directly from the thread-bail 40 to the surface of the cop-tube C and will assume a position as indicated by the dotted line in Fig. 4. Now, as the thread-guide 16 approaches the inward end of its traverse its convex face will ride over the length of 75

yarn y' and cause it to be picked up in the groove or slot 33 of the guide. Immediately the guide picks up the yarn in this manner it is traversed thereby back and forth along the length of the cop-tube C to build the cop, cone or other form 80 of package with a warp wind, the yarn being laid in helical turns crossing and recrossing each other to form overlying layers constituting the body of the package.

The operation of the winding machine continues until the package has reached the desired size, whereupon the machine is stopped, usually through the intermediary of sizing mechanism, so-called, as generally provided on machines of the present type. The full package is doffed from the cop-holder 5 and the machine prepared for winding another package in the same manner as hereinabove described. To set the reserve winding device to operate during the initial stages of the winding it only is necessary to swing the control-member 55 back into position to engage its detent-latch 64 in under the disk 68. This operation is performed by placing the finger upon the lever 61 to swing the member 55 upwardly to restore the detent-latch in detained position under 100 the disk 68.

During this operation the finger-lever 61 engages against the rearward end of the arm 92 of the lever 88 to swing the latter to release its pawl 89 from the ratchet 81. The manual operation 105 of the member 55 further causes the curved arm 53 on the controller 52 to engage against the finger 98 on the spring-pawl 94 whereby to release the latter from the ratchet 81. In this manner the ratchet is freed to permit the spring 76 to return 110 the disk 68 to its initial position with the radial stop-finger 83 bringing up against the side of the lever 93 as shown in Fig. 6. Upon the release of the finger-lever 61 the pawls 89 and 94 are again returned into engagement with the ratchet and 115 the device is ready for another cycle of operations.

It will be observed from the foregoing that the present invention provides a simple and efficient 120 device for effecting the winding of a reserve length of yarn on the cop-tube or other support before the commencement of the winding of the package.

The device can be adjusted to secure any desired length of yarn in the reserve winding in accordance with requirements and when once adjusted will operate repeatedly at the start of each package. The setting of the device merely requires the movement of a single element and the means which controls the yarn to wind a reserve length on the cop-tube is convenient and easy 130 to thread with the same motion of the hand as ordinarily required in preparing the machine to operate without the reserve winding.

The reserve winding device is universally applicable to various types of winding machines 135 without alteration in construction or arrangement of the mechanism thereof. Moreover it can be readily attached and adjusted in position and is compact in size, efficient in operation and not liable to breakage or getting out of order.

While the device is herein described and illustrated as embodied in a preferred form of construction, it is to be understood that modifications may be made in the structure and arrangement of its mechanism and in the method 145 of adapting it to winding machines of other types than that herein shown, without departing from the spirit and scope of the invention. Therefore, without limiting myself in this respect, I claim:

1. In a winding machine, the combination of 150

- means for rotating a yarn-receiver, a thread-guide for traversing yarn longitudinally of the axis of the receiver, means to effect relative reciprocation between the yarn-receiver and thread-guide, a thread-bail across which the yarn leads as it is wound on the receiver, yarn-controlling means arranged between the thread-bail and the yarn-receiver and adapted to engage the yarn to direct it onto the receiver at a point beyond 5 the zone of traverse in winding the package, and means to operate the yarn-controlling means to release the yarn to cause it to feed from the thread-bail to the package in position to be picked up by the thread-guide and traversed thereby 10 throughout the length of the package being wound.
2. In a winding machine, the combination of means for rotating a yarn-receiver, a thread-guide for traversing the yarn longitudinally of 20 the axis of the receiver to build a package with a warp wind, said yarn-receiver and thread-guide being adapted to separate as the package increases in diameter, and a reserve yarn winding device arranged to recede from the receiver during separation of the thread-guide therefrom, said device comprising a yarn-controller for guiding the yarn to deposit it on the end of the receiver beyond the zone of traverse for winding 25 the package, and automatically-operated means for actuating the yarn-controller to release the yarn to adapt it to be traversed by the thread-guide.
3. In a winding machine, the combination of means for rotating a yarn-receiver, a reciproca- 30 ble thread-guide movable away from the axis of the receiver during the growth in the winding, means for reciprocating the thread-guide, and a reserve winding device mounted to move with the thread-guide during its recession from the yarn- 35 receiver, said device comprising means for guiding the yarn during a predetermined number of rotations of the receiver to deposit it on the end thereof in coils lying outside of the zone of traverse of the yarn in winding the package.
4. In a winding machine, the combination of means for rotating a yarn-receiver, a traverse-frame adapted to recede from the axis of the receiver, a thread-guide reciprocable on the 40 traverse-frame to traverse the yarn longitudinally of the axis of the receiver, means for reciprocating the thread-guide, and a reserve winding device mounted on the traverse-frame to move therewith and having means for initially engaging the yarn to restrain it from being traversed 45 by the thread-guide whereby to cause the yarn to be wound about the end of the receiver in a predetermined number of coils disposed beyond the zone of traverse of the thread-guide.
5. In a winding machine, the combination of 50 means for rotating a yarn-receiver, a traverse-frame adapted to recede from the axis of the yarn-receiver during the winding, a thread-guide reciprocable on the traverse-frame to traverse the yarn longitudinally of the receiver to build a warp wound package thereon, a thread-bail on the traverse-frame extending parallel with the path of the thread-guide to guide the yarn there- 55 to, a yarn-controller arranged adjacent the thread-bail and adapted to guide the yarn as it leads therefrom to feed it to the yarn-receiver at a point beyond the zone of traverse of the thread-guide, and means for automatically operating the yarn-controller to cause it to release the yarn to adapt it to feed across the thread-bail in posi- 60
- tion to be picked up by the thread-guide to be traversed thereby to wind the package.
6. In a winding machine, the combination of a winding-spindle for rotatably supporting a 65 yarn-receiver, means for rotating the spindle, a traverse-frame pivoted to swing away from the winding-spindle, a thread-guide reciprocable on the traverse-frame to traverse the yarn longitudinally of the spindle to build a warp wound package on the receiver, means to reciprocate the 70 thread-guide, a thread-bail on the traverse-frame arranged substantially parallel to the surface of the yarn-receiver to adapt the yarn to draw thereacross as it feeds to the thread-guide, a yarn-controller arranged adjacent the end of the thread-bail and provided with means for guiding the yarn to direct it onto the yarn-receiver at a point beyond the zone of traverse of the thread-guide, and means for automatically operating the 75 yarn-controller to release the yarn to adapt it to draw across the thread-bail in position to be picked up by the thread-guide to be traversed thereby to wind the package.
7. In a winding machine, the combination of a 80 winding-spindle for supporting and rotating a yarn-receiver, means to rotate the winding-spindle, a traverse-frame pivoted to swing on an axis parallel with that of the winding-spindle, a thread-guide reciprocable on the traverse-frame longitudinally of the axis of the winding-spindle, means for reciprocating the thread-guide, means on the traverse-frame across which the yarn draws as it feeds to the traverse-frame, a yarn-controller arranged between said last-named means and the winding-spindle and adapted to 85 hold the yarn during the initial stages of the winding to direct it onto the receiver at a point beyond the zone of traverse of the thread-guide, and means for actuating the yarn-controller to release the 90 yarn to cause it to feed to the receiver at a point within the zone of traverse of the thread-guide to be picked up thereby to traverse it to wind the package.
8. In a winding machine, means for rotating a 95 yarn-receiver, a thread-guide, means for traversing the thread-guide longitudinally of the axis of the receiver to build a warp wound package thereon, a thread-bail arranged substantially parallel to the surface of the yarn-receiver at the rear of the thread-guide, yarn-controlling means 100 positioned to engage the yarn between the thread-bail and yarn-receiver to hold it out of the path of the thread-guide, and means for automatically actuating the yarn-controller to release the yarn therefrom to cause it to assume a position on the 105 thread-bail within the path of the thread-guide to be picked up thereby and traversed to wind the package.
9. In a winding machine, the combination of 110 means for rotatably supporting a yarn-receiver, a traverse-frame arranged for relative recession with respect to the receiver during the growth in the winding, a thread-guide reciprocable on the traverse-frame to traverse yarn longitudinally of the axis of the receiver, a yarn-controller mounted on the traverse-frame in position to guide the 115 yarn to the receiver at a point outside the zone of traverse of the thread-guide, a ratchet-disk, means on the yarn-controller engageable with the disk to hold the yarn-controller in predetermined 120 position during the initial stages of the winding, a lever pivotally mounted on the traverse-frame to adapt it to be rocked by the reciprocating motion of the thread-guide, a pawl carried by said lever to engage the ratchet-disk to rotate the lat- 125

ter to release the latch on the controller, and means operative upon release of said latch to move the controller into position to release the yarn to adapt it to be picked up by the thread-guide to be traversed thereby.

10. In a winding machine, the combination of means for rotatably supporting a yarn-receiver, a traverse-frame, means to permit separation of the yarn-receiver and traverse-frame during the winding, a thread-guide reciproicable on the traverse-frame to traverse yarn to wind a package on the receiver, a bracket attachable to the traverse-frame, a yarn-controller mounted on said bracket in position to guide the yarn to the receiver at a point outside the zone of traverse of the thread-guide, and automatic means carried by the bracket and adapted to be actuated by the reciprocating movement of the thread-guide to cause operation of the yarn-controller to release the yarn to adapt it to be picked up by the thread-guide to thereafter be traversed thereby.

11. In a winding machine, the combination of means for rotating a yarn-receiver, a traverse-frame, a thread-guide reciproicable on the traverse-frame, means to permit separation of the yarn-receiver and traverse-frame during the growth of the package, a bracket attachable to the traverse-frame, a forked yarn-controller rockable on said bracket, means for normally maintaining said yarn-controller in position to guide the yarn to the receiver at a point outside the zone of traverse of the thread-guide, and means actuated by the reciprocation of the thread-guide at a predetermined stage in the winding to release the yarn from the controller to cause it to be picked up by the thread-guide.

12. In an attachment for winding machines, the combination of a rotatable ratchet-disk formed with a slot extending through its rim in the direction of its axis of rotation, a yarn-controller pivoted to rock on an axis crossing the axis of the ratchet-disk and formed with a guide-way for the yarn and a projecting latch adapted to engage beneath the rim of the ratchet-disk, means adapted to be operated by a going member of the winding machine to intermittently rotate the ratchet-disk to bring its opening into register with the latch on the controller, and means for swinging the controller upon release of its latch from the ratchet-disk whereby to cause it to release the yarn held in its guide-way.

13. In an attachment for winding machines, the combination of a rotatable ratchet-disk having a radial opening in its periphery, a yarn-controller pivoted on an axis at right-angles to the axis of the disk and having a latch adapted to engage beneath said disk and to pass through the opening therein, said controller having means for guiding a strand in a predetermined course, means adapted to be operated from a going part of the winding machine to intermittently turn the ratchet-disk to bring its opening into register with the latch on the controller, and a spring for rocking the controller upon release of its latch to cause it to move into a position to release the strand.

14. In a device of the type specified, the combination of a rockable member having a latch projecting from its side and a yarn-receiving fork at its end, a spring for rocking said member, a ratchet-disk journaled to adapt its lower face to engage with the latch on said member and provided with a radial opening through which the latch may pass, a lever, a pawl on said lever adapted to engage the teeth on the ratchet to

turn the disk into position to release the ratchet through its opening, a pawl for preventing retrogressive movement of the ratchet, and means on said rockable member adapted to engage both of said pawls to release them from the ratchet when said member is adjusted into position to engage its latch under the disk.

15. In a device of the type specified, the combination of a rockable member having a yarn-controller for directing a strand in a predetermined course and formed with a latch on its side, a ratchet-disk journaled on an axis arranged at right-angles to the axis of the rockable member to adapt its under side to engage the latch thereof and formed with a radial opening through which the latch may pass, a lever, a yieldable pawl on said lever for engaging the teeth on the ratchet-disk to rotate the latter, a pawl for preventing retrogressive movement of the ratchet-disk, a spring for turning the ratchet-disk in a direction opposite to that in which it is turned by the pawl on the lever, means on the rockable member engageable with said pawls to release the latter to adapt the disk to be rotated by its spring, and a stop-element on the disk engageable with the lever to limit the turning movement of the disk under the action of its spring.

16. In a device of the type specified, the combination of a rotatable ratchet-disk formed with a radial opening, a lever, a pawl on said lever adapted to engage the teeth on the ratchet to advance the disk in one direction, a spring for turning the disk in the opposite direction, stop-projections on the disk engageable with the lever to limit the turning movement of the disk in each direction, a pawl for preventing retrogressive movement of the disk under the action of its spring, a rockable member having a latch adapted to engage the under side of the disk and to pass through the opening therein, said rockable member provided with means for guiding a strand of yarn, a spring for rocking the rockable member upon release of its latch from the disk, and means on the rockable member engageable with both of the pawls to release the latter from the ratchet to permit the disk to be returned to first position under the action of its spring with one of the stop-projections engaging the lever.

17. In a device of the type specified, the combination of a bracket formed with a rest, a ratchet-disk journaled to rotate on said rest and provided with a radial opening in its side, a lever, a pawl on said lever engageable with the teeth of the ratchet to advance the disk, a spring for turning the disk in the opposite direction, a pawl for normally preventing retrogressive movement of the disk under the action of its spring, a rockable member having a latch engageable beneath the bottom of the disk and adapted to pass through the opening in its side, said rockable member having means for guiding a strand of yarn, a finger-lever on said member, a spring for rocking the rockable member upon release of its latch from the disk, and means on the rockable member engageable with each of the pawls to release them from the ratchet to permit the disk to be returned to initial position when the rockable member is rocked to engage its latch beneath the disk.

18. In a winding machine, means for rotating a yarn-receiver, means for traversing yarn longitudinally of the receiver to dispose it in concentric layers with a warp wind, said yarn-receiver and traversing means being arranged for separation during the growth in diameter of the pack-

age being wound, and means for holding the yarn out of the path of and free from contact with the traversing means during the initial stages of the winding whereby to guide it onto the yarn-receiver at a point beyond the normal zone of traverse of the traversing means to wind a predetermined number of coils of reserve yarn at the end of the yarn-receiver.

19. In a winding machine, means for rotating a yarn-receiver, means for traversing yarn longitudinally of the receiver to deposit it in concentric layers of a length equal to the length of the package to be wound, means permitting separation of the yarn-receiver and traversing means

during the growth in diameter of the winding, controlling means adapted to hold the yarn away from the traversing means at the start of the winding and to direct it onto the yarn-receiver at a point beyond the range of movement of the traversing means, and means to operate the yarn-controlling means after a predetermined number of coils of yarn have been wound onto the end of the receiver whereby to release the yarn to cause it to be engaged by the traversing means to traverse it throughout the length of the package being wound.

GUSTAF S. BECKMAN.
